UNITED STATES PATENT OFFICE.

JOHN B. FREYSINGER, OF NEW BRITAIN, CONNECTICUT, ASSIGNOR TO NORTH & JUDD
MANUFACTURING COMPANY, OF NEW BRITAIN, CONNECTICUT.

BUCKLE.

Application filed March 19, 1925. Serial No. 16,797.

This invention relates to buckles of that type commonly used for belts for personal wear and its object is to provide a novel construction of gripping member whereby the 5 free end portion of the belt will be securely held and belts of various thickness will be accommodated. The invention is illustrated in the accompanying drawing and will be hereinafter first fully described and then 10 particularly defined in the claim.

In the drawing,—

Figure 1 is a longitudinal section of a buckle embodying my invention.

Figure 2 is a rear elevation of the buckle.

Figure 3 is a detail perspective of the gripping member, and

Figure 4 is a detail perspective of the anchoring member.

The body member of the buckle comprises 20 a front plate 1 having side flanges 2 which, near one end, are formed with inturned lips or lugs 3 constituting guides for introducing the free end of the belt and preventing the body member of the buckle from swinging 25 away from the line of the belt.

Beyond the inner ends of the lips 3, the flanges are formed with ears or extensions 4 having openings or seats in which studs or trunnions 5 on the gripping member are 30 engaged for rocking movement. The gripping member may be formed from sheet metal and comprises a fulcral plate 6 the width of which is substantially equal to the distance between the flanges 2, the trunnions 5 or studs 5 being formed to project 35 from the side edges of the plate immediately adjacent the lip 7 which is formed by bending one end of the plate substantially at a right angle and extends toward the front 40 plate and the belt body to bind the free end portion of the belt against the front plate.

The fulcral plate is offset transversely, as at 8, between its ends, and the portion of the plate between the offset and the end more 45 remote from the trunnions is arranged at an obtuse angle to the portion carrying the trunnions. The gripping plate 9 is carried upon the front face of the fulcral plate and is shown as being formed integral therewith 50 by doubling the blank upon itself, as at 10. The gripping plate rests flat against the relatively inclined portion of the fulcral plate and projects beyond the offset 8 so that the 55 enner end portion of the plate is free and

may yield to a thick belt without releasing 55 the same. The free end of the gripping plate is bent forwardly to form a gripping lip 11 adapted to clamp the belt against the front plate of the buckle body.

The "fixed" end of the belt may be anchored in any approved manner. I have shown the gripping member as provided with rearwardly projecting lugs or ears 12 to pivotally receive trunnions 13 on the side edges of an anchoring clamp 14 which is essentially an angle lever of plate form having spurs or teeth 15 along one edge to penetrate the end of the belt disposed against the rear face of the fulcral plate. The power arm of the lever is adapted to extend over 70 and bear upon the inner portion of the gripping member, and it is provided with a tongue or finger piece 16 to facilitate release of the belt when a change of belts is 75 desired.

It will be readily seen from the foregoing description, taken in connection with the accompanying drawing that I have provided a very simple inexpensive but efficient buckle whereby a belt will be securely held 80 and thin and thick belts, within reasonable limits, will be secured alike. The provision of binding lips upon both the fulcral and the gripping plates effects engagement with the belt at two points so that the clamping 85 force is exerted over a somewhat extended area of the belt, and the peculiar form of the gripping member imparts thereto spring qualities without any loss of strength. The gripping lip is spaced laterally from the 90 fulcral axis so that after a belt is engaged, any tendency of the belt to move out of the buckle will draw the lip toward a position directly between the axis and the front plate so as to more firmly bind the belt.

It will be understood that to secure the free end of the belt, the gripping member is swung rearwardly so that the gripping lips will extend substantially parallel with the buckle front plate, leaving a clear space for the insertion of the belt. After the belt is inserted, the gripping member is swung forwardly causing the gripping lips to bind the belt against the front plate and securely hold it against withdrawal until such time as the gripping member is again swung rearwardly.

Having fully described my invention what

I claim as new and desire to secure by Letters-Patent, is:

A belt buckle including a body, and a lever comprising a fulcral plate pivotally mounted upon the body and having a belt-gripping lip adjacent and at one side of the fulcral axis and a transverse offset adjacent and at the opposite side of the fulcral axis, the portion of the plate between the lip and the offset being inclined away from the body and the portion of the plate at the side of the offset more remote from the axis being free and relatively inclined to closely follow

the conformation of the body, a gripping plate carried by and resting close against the front face of the inclined portion of the fulcral plate and extending beyond said inclined portion whereby to define a free end portion terminating between the offset and the fulcral axis and having a forwardly projecting gripping lip, and a clamping lever pivotally mounted on the rear side of the fulcral plate.

In testimony whereof, I have signed this specification.

JOHN B. FREYSINGER.
